S. THOMPSON.
MACHINERY FOR SPOOLING YARN FROM THE COP.

No. 10,557.

Patented Feb. 21, 1854.

UNITED STATES PATENT OFFICE.

SMITH THOMPSON, OF NEWBURYPORT, MASSACHUSETTS.

SPOOLING YARN FROM THE COP.

Specification of Letters Patent No. 10,557, dated February 21, 1854.

To all whom it may concern:

Be it known that I, SMITH THOMPSON, of Newburyport, in the county of Essex and State of Massachusetts, have invented a new and useful Improvement in Machinery 5 for Spooling Yarn from the Cop; and I do hereby declare that the same is fully described and represented in the following specification and the accompanying drawings, letters, figures, and references thereof.

Of the said drawings, Figure 1, denotes a front elevation, and Fig. 2, a sectional side view of a cop, its stand, support bar, friction beam, and thread guides as they appear 15 in a spooling machine constructed in my improved manner.

In the said drawings, A is the cop; B, the stand, or support of it; C, the support bar; D, the friction beam, and E, F, the yarn or 20 thread guides.

In the ordinary spooling machine the back guide, F, is made perfectly stationary. When this is the case, the draft on the yarn, while it is being unwound from or 25 near the bottom of the cop being much increased from what it is while the yarn is being unwound from or near the upper part or rest of the cop, the yarn is liable to be broken. Besides this cause of variation of 30 the draft, it frequently occurs from others. As the beam, D, is covered with cloth in order to produce friction on the yarn, there is a uniformity of friction while the yarn is passing over and in contact with it, for 35 it always touches the beam in the same arc, $a b c$, but should the arc be diminished, the friction will be reduced in a corresponding degree.

My invention has for its object to lessen 40 the said arc or the friction under any in-

jurious increase of the draft, and to do it proportionally to such increase. I accomplish this by making the back, F, movable and to hang on the yarn and freely rise and fall within a socket, d, the ordinary weight 45 or pressure of the guide being adjusted to such draft as it will be safe for the yarn to endure without danger of breakage therefrom. An increase of draft will cause the back guide to be lifted and thereby diminish 50 the arc of contact of the yarn with the friction beam.

The dotted lines not only show the guide as raised under an increase of draft, but the position the thread assumes under such circumstances, the arc of bearing on the friction beam being reduced to $a b$, it being 55 supposed that the said beam is a round one.

I do not confine my invention to the precise form of movable guide used, nor to the 60 making it of weight sufficient to produce the requisite pressure on the thread, as such pressure may be obtained to it by a spring properly applied to it, or by other well known means, such variations being changes 65 in construction without any material change in the principle of the invention.

I claim—

The regulator guide as combined with the friction beam and made to hang on the yarn 70 and be capable of being raised by it substantially in manner and for the purpose as specified.

In testimony whereof, I have hereto set my signature this second day of July A. D. 75 1853.

SMITH THOMPSON.
